*Primary Examiner—Bernard Ansher**Assistant Examiner—P. Hyder**Attorney, Agent, or Firm—Hawes & Fischer***[57] CLAIM**

The ornamental design for a housing for a magnetic blade sharpener, as shown and described.

DESCRIPTION

FIG. 1 is a perspective view showing the top, the front and the left side of the housing for a magnetic blade sharpener showing my new design;

FIG. 2 is a left side elevation view, this view and the opposite right side elevation being of identical design, the broken lines representing safety razors are shown for illustrative purposes only and form no part of the claimed design;

FIG. 3 is a top plan view;

FIG. 4 is a bottom plan view; and,

FIG. 5 is a front elevational view, this view and the opposite rear elevation being of identical design.

FIG. 1

FIG. 2

FIG. 3

FIG. 4

FIG. 5
